The ornamental design for an air cooled floor polishing machine, as shown and described.

DESCRIPTION

FIG. 1 is a front perspective view of an air cooled floor polishing machine showing our new design;
FIG. 2 is a top plan view thereof;
FIG. 3 is a bottom plan view thereof;
FIG. 4 is a left side elevation view thereof;
FIG. 5 is a right side elevation view thereof;
FIG. 6 is a front elevation view thereof; and,
FIG. 7 is a rear elevation view thereof.

FIG. 1

FIG. 2

FIG. 3

FIG. 5

FIG. 4

FIG. 7

FIG. 6
